UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

OIL DASH-POT.

1,400,863.

Specification of Letters Patent.

Patented Dec. 20, 1921.

Application filed May 17, 1917. Serial No. 169,228.

To all whom it may concern:

Be it known that I, GEORGE A. BURNHAM, a citizen of the United States, residing at Saugus, in the county of Essex and State of 5 Massachusetts, have invented an Improvement in Oil Dash-Pots, of which the following is a specification.

My invention relates to time limit relays of the type in which an oil dash-pot is used 10 to retard the motion of the core, the rate of leakage of oil by the plunger determining the time interval between the occurrence of the overload and the operation of the relay switch.

15 When an oil dash-pot time limit relay is operated under severe overloads, there is a pumping action set up which tends to eject oil around the stem of the plunger rod. Each action of the relay diminishes by a 20 small amount the quantity of oil in the dash-pot or cylinder, and eventually the action of the relay becomes irregular and performs as an ordinary circuit breaker, the gradual loss of oil destroying the time limit features.

25 Consequently, an object of my invention is to provide means whereby this objectionable operation and loss of oil is prevented, and the relay thereby continually maintained in operating order.

30 The means by which this object is attained is to maintain a body of oil in a suitable container, at such a height above the opening into the dash-pot that the energy of the stream of oil issuing from the opening of the 35 dash-pot during pumping action of the piston is expended in creating eddy currents in the body of oil, to such an extent that the remaining energy in the stream, due to its velocity, is insufficient to overcome the sur-

40 face tension of the body of oil above the dash-pot and break through the surface of the oil and escape from the cylinder as a jet.

A further object of my invention is in the 45 provision of a relay having a suitable receptacle for the dash pot to serve as a container for the oil for the purpose above set forth.

Figure 1 shows a front elevation, partly in section, of an oil dash-pot time limit relay embodying my invention.

50 Fig. 2 is a sectional elevation of Fig. 1 along line 2-2.

Fig. 3 is a sectional plan view of Fig. 1 along line 3-3.

Fig. 4 is an elevation of the oil retainer.

Fig. 5 illustrates a modified form of my 55 invention.

As here shown, the oil dash-pot time limit relay comprises the core 10 operable within the coil or solenoid 11 which is inclosed in a case 12 adapted to be secured to a base or 60 panel 12'. The upper part of core 10 is adapted to engage contacts (not shown), at some predetermined time after the occurrence of an overload, to control a suitable circuit. A rod 13 depends from the lower 65 end of plunger on core 10 and terminates in a piston 14 which is inclosed in a cylinder or dash-pot 15. Cylinder 15 is secured, by screw threads, to a slotted tube 17 depending from the solenoid 11 and concentric with 70 core 10 and piston 14.

Bushing 16 is secured in the end of tube 17 adjacent the cylinder 15, and has a concentrically located opening 16' for the passage of piston rod 13 therethrough. Rod 75 13, attached to piston 14 is adjustable in plunger 10 to vary the load at which the relay will operate and is provided intermediate its length, with a knurled nut 18 fixed to piston rod 13. Nut 18 is of smaller 80 diameter than the inner diameter of said tube 17 and in the lowest position of plunger 10 and piston 14, is moved downward with said piston to engage bushing 16 to thereby limit the downward movement of piston 14 85 and plunger 10.

A casing 19 is provided to inclose the cylinder 15 and allied parts, and has compartments 20 in which cylinders 15 are disposed which compartments are adapted to contain 90 oil. Casing 19 is attached to solenoid inclosing case 12 by a wing nut and threaded rod.

In the modified form of oil dash-pot time limit relay embodying my invention, as 95 illustrated in Fig. 5, wherein a solenoid and dash-pot are combined as an independent unit, an individual casing 21 is provided for each dash-pot, to maintain the oil level above the opening into the dash-pot.

In the operation of the usual type of oil dash-pot time limit relay, the piston 14 normally occupies a position at the bottom of the dash-pot or cylinder 15, and a column of oil is maintained above the piston to some 105 level as $a-a$, Fig. 2. With a current flow in solenoid 11 in a normal excess of that for which the plunger 10 is set, plunger 10 is

drawn within solenoid 11 and raises piston 14, creating a partial vacuum between the under side of piston 14 and cylinder 15. Due to the difference of pressure existing between 5 the opposite sides of the piston, oil is forced between the piston and the cylinder to fill the space beneath the piston, and the piston and cylinder are made of such diameter that a suitable leakage may take place therebetween. If the overload is moderate, the rate 10 at which the piston 14 is raised in cylinder 15 is approximately equal to the rate of flow of oil between the piston and cylinder and consequently the oil in the dash-pot above 15 the piston is maintained at a substantially constant level.

With a very heavy load, however, the rate of upward movement of piston 14 becomes much greater than the rate of downward flow 20 of oil around the piston and consequently the oil level in the cylinder or dash-pot 15 is raised, and a "pumping" action takes place, which results in a spurt of oil through the opening 16', and the consequent loss of the 25 oil. Every operation of the relay under heavy overload results in an additional loss of oil until finally, due to insufficient oil supply, occasioned by the loss of oil, the action 30 of the relay becomes erratic, and soon functions only as a circuit breaker.

The pumping action of the oil dash-pot of time limit relay is inherent to the design of the apparatus, and can not be obviated.

In the operation of a relay embodying my 35 invention, the compartment 20 surrounding dash-pot 15 is filled with oil to such a level that when the dash-pot is disposed within the compartment, the oil level will assume some level $b-b$, Fig. 2, substantially above the 40 opening 16' communicating with the dash-pot 15.

The operation of the relay with the oil at this level $b-b$, for small current overloads, and consequently but slight pumping 45 action, is substantially the same as in the ordinary type of oil dash-pot relay, the operation of which has been previously explained.

Under heavy overloads, and strong pumping action, however, the operation is materially different. When the piston is raised 50 under heavy overload, and pumping action occurs, a flow of oil is set up through opening 16' of cylinder 15, as in the ordinary type of oil dash-pot relay. This stream 55 of oil has considerable velocity when it issues from opening 16', and in the ordinary relay,

is thrown from the dash-pot and lost. In the apparatus embodying my invention, however, this stream, flowing at comparatively high velocity, enters the body of oil maintained in compartment 20 above opening 16'. This body of oil serves to absorb the velocity of the stream by causing it to set up eddy currents in the body of oil to such an extent that when the stream reaches the top surface 65 $b-b$, the pressure due to its velocity is insufficient to overcome the surface tension of the oil and break through the surface, and consequently no spurt or jet of oil escapes from the apparatus. 70

The oil level $b-b$ must be initially of such a height above the opening 16' that, under excessive overloads, the velocity of the oil stream issuing from said opening will be absorbed by the oil above the opening to such 75 a degree that the pressure of the oil jet, due to its remaining velocity, is below that necessary to overcome the surface tension of the oil. When this condition is initially fulfilled, there will never be any spurt of 80 oil from the apparatus, and the consequent loss thereof, and the relay will be continually maintained in operative order.

I claim:

1. A retardation device comprising a 85 solenoid, a core operable therein, a dash pot comprising a cylinder adapted to contain oil depending from said solenoid, a piston operable therein, a piston-rod connected with said piston extended through the end of said 90 cylinder and connected with said core, and an inclosing casing for said cylinder adapted to receive oil.

2. A retardation device comprising a 95 solenoid, an inclosing casing therefor, a core operable within said solenoid, a dash pot comprising a cylinder adapted to contain oil depending from said solenoid, a piston operable therein, a piston-rod connected with 100 said piston extended through the end of said cylinder and connected with said core, and an inclosing casing for said cylinder adapted to receive oil having means for detachably securing it to the solenoid inclosing casing.

In testimony whereof, I have signed my 105 name to this specification, in the presence of two subscribing witnesses.

GEORGE A. BURNHAM.
